UNITED STATES PATENT OFFICE.

SULLIVAN HASLETT, OF BROOKLYN, NEW YORK.

IMPROVEMENT IN SURVEYORS' TARGETS.

Specification forming part of Letters Patent No. **221,916**, dated November 25, 1879; application filed April 21, 1879.

To all whom it may concern:

Be it known that I, SULLIVAN HASLETT, of Brooklyn, in the county of Kings and State of New York, have invented a new and useful Improvement in Surveyors' Targets; and I do hereby declare that the following is a full, clear, and exact description of the same, reference being had to the accompanying drawings, and to the letters of reference marked thereon, making part of this specification.

This invention is in the nature of an improvement in surveyors' targets; and the invention consists in a surveyor's target constructed with a micrometer adjusting-screw and clamping-screws, whereby the target may be accurately adjusted to the divisions on the surveyor's staff, and whereby the sliding portion of the staff itself may be adjusted, in the manner hereinafter more particularly described.

In the accompanying sheet of drawings, Figure 1 is a front view of target and staff; Fig. 2, a side view of my invention; Fig. 3, a reverse side view of same; Fig. 4, a section through line *x x*, Fig. 1; Fig. 5, a cross-section of adjusting devices, showing micrometer-screw and springs; Fig. 6, a front view of adjusting devices, with sleeves partly in section, in line *y y*, Fig. 5; and Fig. 7, front view of staff, showing interior slide and interior markings.

Similar letters of reference indicate like parts in the several figures.

In surveying and leveling, the well-known target is ordinarily adjusted to the divisions on the surveyor's staff by hand, and the frequent inaccurate adjustment in this way has led to errors, and also to loss of time in making the adjustment. The same remark applies also to the adjustment of the sliding portion of the surveyor's staff—that is, the accurate adjustment of the slide to the divisions of the scale formed between the sliding surfaces of the staff.

To obviate these difficulties I construct my target *A*, which may be of any desired size or shape on its face, with a bracket or sleeve, *B*. This sleeve is firmly secured to the back of the target, and is preferably rectangular in shape. Within the sleeve *B* is accurately fitted a second sleeve, *C*, which is not attached

to the target, but which is constructed to permit the surveyor's staff *D* to pass through it, with sufficient space between the surface of the staff *D* and the inner surface of the sleeve *C* to allow the interposition of flat springs *a b c d*, which are secured within the sleeve *C*. The sleeve *B* on one side has formed in it a slot, *e*, which slot is parallel with the length of the staff *D*, and the sleeve *C* likewise has a small slot, *j*, formed in one of its sides, which last-mentioned slot is also parallel with the staff *D*.

To the sleeve *C* is fixed a stud, *f*, which passes through the slot *e* in the sleeve *B*. This stud has screw-threads formed in it, which receive the threads of a screw, *g*, with a milled head, *h*, formed on it, and through the sleeve *B* passes a screw, *i*, which screw enters into the slot *j* in the sleeve *C*.

To the rear side of the sleeve *B* is fixed or formed a projection, *k*, and within this projection is fitted a sliding nut, *l*. This nut has made in it screw-threads into which passes a screw, *E*, working in bearings *m* and *n*, formed on the rear side of the sleeve *C*, the screw *E* being provided with a milled head, *o*.

The staff *D* employed is the ordinary surveyor's staff, with the divisions *r* on its face, and made in two parts, *s* and *t*, which slide together, and also with divisions *v* on the slide *w*.

My target, constructed substantially as above described, is operated as follows: It is moved by hand until the dividing-line *y* on its face is nearly coincident with the marking on the scale *r* on the face of the staff, or as nearly as may be to the height indicated by the surveyor, in which position it is held by turning the clamping-screw *g*, which forces the spring *d* against the side of the staff, tightly clamping the target in position. Then, when a more accurate adjustment requires the target to be moved carefully up or down from its clamped position, as before stated, the micrometer-screw *E* is turned to the right or left, thereby raising or lowering the target with accuracy to a given position on the staff. This raising and lowering of the target is accomplished by the action of the micrometer-screw working through the nut *l*, which is fixed to the sleeve *C*, so that as this sleeve is clamped

to the staff by the binding-screw *g* the sleeve *B* slides over the surface of the sleeve *C*, carrying the target *A*, which is fixed to it, as before stated. This action of the micrometer-screw *E* not only adjusts the target on the staff with great nicety, but it also holds the target fixed in whichever position it may be adjusted by the action of the screw *E*.

The purpose of the slot *e* in the sleeve *B* is to permit the sliding movement of the sleeve without interruption from the binding-screw *g*.

To adjust the sliding parts of the staff to the scale *v* on the slide *w*, a plate, *a²*, with a screw-hole formed therein, is countersunk and fastened to the side of the face-section or sliding part *s* of the staff, and the sleeve *B* is moved up to that plate, or the staff is otherwise adjusted so that the screw *i* may enter into the screw-hole formed in the plate *a²*, thereby firmly clamping the sleeve *B* to the face or sliding part *s* of the staff, and when so fixed, by releasing the clamping-screw *g* and turning the micrometer-screw *E*, the two sections of the staff *s* and *t* will be made to slide on each other up or down, as may be desired, till an approximately-accurate adjustment of the height of the staff is obtained. Then by tightening the screw *g* the accurate adjustment is effected by the action of the micrometer-screw *E*, which causes the sleeve *B* to slide up and down on the sleeve *C* as the screw is turned to the right and left; and since the sleeve *B* is practically screwed fast to the front sliding portion, *s*, of the staff, as before described, this front portion of the staff is carried by the sleeve *B* by its movement, as before stated.

When adjusting the target so that this ad-

justment of the length of the staff by the micrometer-screw is desired, it is necessary to slacken up the clamping-screw *g*, so as to permit the two sections of the staff to freely slide upon each other. The slot *j* in the sleeve *C* permits the sleeve *C* to move up and down unobstructed by the screw *i*.

The purpose of the springs *a*, *b*, and *c* is to cause the target to slide steadily without wobbling and with ease on the staff *D*. The spring *d* also assists in that particular, and besides acts as a clamp in connection with the screw *g*, as hereinbefore described.

Having now described my invention, what I claim as new, and desire to secure by Letters Patent, is—

1. A surveyor's target, *A*, in combination with sleeves *B* and *C*, micrometer-screw *E*, and staff *D*, substantially as and for the purpose described.

2. In a surveyor's target, the combination of a micrometer-screw, *E*, a clamping-spring, *a*, and clamping-screw *i*, substantially as and for the purpose described.

3. In a surveyor's target, the combination of a micrometer-screw, *E*, a clamping or holding screw, *g*, and sliding sections *s* and *t* of a surveyor's staff, *D*, substantially as and for the purpose described.

4. In a surveyor's target, the combination of the staff *D*, the sleeve *B*, sleeve *C*, micrometer-screw *E*, clamping-screws *g* and *i*, and springs *a b c d*, substantially as and for the purpose shown and described.

SULLIVAN HASLETT.
